No. 37,130.

Patented September 13, 1904.

UNITED STATES PATENT OFFICE.

GEORGE W. COPE AND WILLIAM L. BERTRAM, OF DETROIT, MICHIGAN,
ASSIGNORS TO ECONOMY STOVE & MANUFACTURING COMPANY, OF
CLEVELAND, OHIO.

DESIGN FOR A STOVE.

SPECIFICATION forming part of Design No. 37,130, dated September 13, 1904.

Application filed August 16, 1904. Serial No. 220,961. Term of patent 7 years.

To all whom it may concern:

Be it known that we, GEORGE W. COPE and WILLIAM L. BERTRAM, citizens of the United States, residing at Detroit, in the county of Wayne and State of Michigan, have invented a certain new, original, and ornamental Design for a Stove, of which the following is a specification, reference being had therein to the accompanying drawings, in which—

Figure 1 is a front elevation, and Fig. 2 is to a side elevation.

What we claim as our invention is—
The ornamental design for stove, as shown.

GEORGE W. COPE.
WILLIAM L. BERTRAM.

Witnesses:

JAS. P. BARRY,
E. D. AULT.
